CONTROL SYSTEM FOR STEAM JET
REFRIGERATING MECHANISM

John E. Haines, Minneapolis, Minn., assignor to
Minneapolis-Honeywell Regulator Company,
Minneapolis, Minn., a corporation of Delaware

Application January 8, 1936, Serial No. 58,121

17 Claims.

(Cl. 62—2)

This invention relates to control systems for refrigerating mechanisms and particularly to that type of refrigerating mechanism comprising evaporators, ejectors and condensers.

5 An object of this invention is to provide a control system for such a refrigerating mechanism whereby the refrigerating mechanism may be readily placed in operation upon a call for cooling, and whereby it may be maintained in operation in an extremely efficient manner.

10 More specifically, an object of this invention is to provide a control system for a refrigerating mechanism of the type specified wherein high pressure steam is admitted to the ejector for a predetermined interval of time upon a call for cooling to place the refrigerating mechanism in operation and then reduced pressure steam is admitted to the ejector to maintain the refrigerating mechanism in operation in an efficient manner.

15 Another object of this invention is to provide a control system for a refrigerating mechanism of the type specified wherein the supply of steam to the ejector is maintained at a substantially constant pressure by a pressure regulating means, and wherein the pressure of the steam admitted to the ejector may be varied in accordance with the condition of the condenser to maintain a constant pressure drop across the ejector regardless of the vacuum existing within the condenser whereby a constant vacuum is maintained in the evaporator.

20 Another object of this invention is to provide a control system for a refrigerating mechanism having an evaporator, an ejector, a condenser and starting and running nozzles wherein steam at high pressure is admitted to the starting nozzles to place the refrigerating mechanism in operation, steam is admitted to the running nozzles at high pressure to aid in placing the refrigerating mechanism in operation and steam is admitted to the running nozzles at a reduced pressure, preferably a constant pressure, to maintain the refrigerating mechanism in operation.

25 Still another object of this invention is to provide a valve means between the evaporator and the ejector which is moved to a closed position when the refrigerating mechanism is not in operation and when the refrigerating mechanism is being placed in operation to prevent the backing up of steam into the evaporator during these periods so that when the refrigerating mechanism is placed in operation the vacuum in the evaporator will be produced more readily than if this steam were allowed to back up into the evaporator.

30 tor whereby the refrigerating mechanism may be rapidly placed in condition for operation.

A further object of this invention is to provide a refrigerating mechanism having a primary evaporator and ejector and a secondary evaporator and ejector, both communicating with a common condenser, the primary evaporator and ejector being maintained in operation at all times and the secondary evaporator and ejector being placed in operation only when the load on the refrigerating mechanism becomes sufficiently great that it can not be handled by the primary evaporator and ejector, along with control means for placing the secondary evaporator and ejector in operation automatically in accordance with the increased load and for preventing communication between the primary and secondary evaporators and the primary and secondary ejectors, respectively, when the secondary evaporator and ejector are being placed in operation.

35 Still another object of this invention is to provide a program switch operated in response to a demand for cooling for performing various sequences of operation more clearly set forth in the annexed specification.

40 Other objects and advantages will become apparent to those skilled in the art upon reference to the accompanying specification, claims and drawings, in which drawings:

Figure 1 is a schematic illustration of a steam jet refrigerating mechanism having a main evaporator and a secondary evaporator with the control system of my invention applied thereto, and

45 Figure 2 is a wiring diagram showing the manner of operation of my control system.

50 Referring now to Figure 1, the main evaporator is designated at 10 and is provided with sprays 11 for spraying the cooling fluid into the evaporator 10. The cooling fluid is delivered to the sprays 11 from some point of use (not shown) through a pipe 12 under the control of a valve 13 which is operated in accordance with the liquid level of the cooling fluid within the evaporator 10 by a liquid level responsive controller 14. The liquid level responsive controller 14 maintains a constant amount of cooling fluid within the evaporator 10. The chilled cooling fluid is drawn from the main evaporator 10 through a pipe 15 and delivered to a point of use for the purpose of cooling.

55 The upper surface of the evaporator 10 opens into a valve 16 having a gate 17. The gate 17 may be operated by a hydraulic motor 18 under the control of a four-way valve 19 which admits

and exhausts liquid to and from the hydraulic motor 18. The valve 19 is moved from one extreme position to the other extreme position by an electric motor designated at 20.

- 5   Mounted on the top of the valve 16 and in
communication therewith is a nozzle box 21 having
starting nozzles 22 and running nozzles 23. Steam is supplied to the starting nozzles 22
10   through a pipe 24 from a steam header 25 under
the control of a manually operated valve 26. Steam is supplied to the running nozzles 23
15   through a pipe 27 from a steam header 28 under
the control of a manually operated valve 29. The
pressure of the steam within the second steam
header 28 is regulated by means of a pressure
10   regulating valve 30 and the upstream side of this
valve 30 may be connected into the high pressure
header 25 as by means of a pipe 31.
The nozzle box 21 is connected by a main
20   ejector 32 to a condenser designated at 33. The
condenser 33 may contain the usual condenser
tubes 34. The condensed steam conveyed to the
condenser 33 by the main ejector 32 may accu-
25   mulate in a condensate chamber 36 and may
be drawn off therefrom through a pipe 37 by
means of a condensate or vacuum pump (not
shown). The condenser 33 may also be connect-
ed to first and second stage ejectors for the
purpose of purging the condenser of air by means
of a pipe 38 in the manner well known in the
art. Condensing water is admitted to the con-
denser by means of a pipe 39 and is discharged
therefrom by means of a pipe 40.
The main steam jet ejector refrigerating mech-
anism so far described may be placed in oper-
ation by placing a vacuum on the condenser 33
and by opening the steam valve 26 for admitting
high pressure steam to the starting nozzles 22
whereby a vacuum is created within the main
40   evaporator 10 to cause flashing into steam of a
portion of the returning cooling fluid flowing
from the sprays 11 in the evaporator 10. This
chills the cooling fluid within the evaporator 10
in a manner well known in the art. After the
45   main refrigerating mechanism is thus placed in
operation the steam valve 29 is opened to admit
steam at a regulated pressure to the running noz-
zles 23 and the valve 26 is closed. This allows
the refrigerating mechanism to be maintained in
50   operation by the pressure regulated steam com-
ing from the regulated pressure steam header
28. The main steam jet refrigerating mech-
anism is preferably maintained in operation at
all times.
The secondary evaporator is designated at 42
55   and may likewise contain sprays 43 which re-
ceive cooling fluid from a point of use through
a pipe 44 under the control of a valve 45 which
valve is operated in accordance with the liquid
60   level in the evaporator 42 by a liquid level re-
sponsive controller 46 to maintain a constant
liquid level within the evaporator 42. A portion
of the cooling fluid is flashed into steam in or-
der to chill the remainder of the cooling fluid
65   in the manner pointed out with reference to the
evaporator 10 and the chilled cooling fluid is
drawn from the secondary evaporator 42 through
a pipe 47 and delivered to a point of use for the
purpose of cooling. The evaporator 42 opens
70   into a valve 48 having a gate 49 which is also
operated by a hydraulic motor designated at 50.
Liquid is admitted to and exhausted from the
hydraulic motor 50 by means of a four-way valve
51 which is spring-biased to one extreme posi-
75   tion and which is moved to the other extreme

position upon energization of a solenoid designated at 52.

The valve 48 in turn opens into a nozzle box 53 having starting nozzles 54 and running nozzles 55. Steam is supplied to the starting nozzles 54 from the high pressure steam header 25 under the control of a valve 58. The valve is moved to either open or closed positions by means of an electric motor 59. Steam at a regulated pressure is admitted to the running nozzles 55 from the regulated pressure steam header 28 under the control of a valve 56 which is moved to either open or closed position by means of an electric motor 57.

The nozzle box 53 connects with a secondary 15
ejector 60 which in turn is connected into the
condenser 33 by means of a conduit 61. The sec-
ondary steam jet ejector refrigerating mechanism
is placed in operation in substantially the same
manner as the main steam jet ejector refrig- 20
erating mechanism by admitting steam to the
starting nozzles 54 and then by admitting pres-
sure regulated steam to the running nozzles 55.

The valves 16 and 48 associated with evaporators 10 and 42 respectively are provided for closing off the evaporators 10 and 42 from the nozzle boxes 21 and 53, respectively, when the secondary steam jet refrigerating mechanism is to be placed in operation. The valves 16 and 48 are closed at this time to prevent the backing up of steam into the evaporators 10 and 42 in order to expedite the placing of the secondary refrigerating mechanism into operation.

The pressure regulating valve 30 is shown to be operated by a conventional hydraulically operated regulating device and may comprise a lever 63 secured to the valve stem of the pressure regulating valve 30 and a chain or cable 64 connecting the lever 63 to a piston rod 65 of a hydraulic motor 66. The hydraulic motor 66 is controlled by a valve located in a valve chest 67 which is operated in accordance with the steam pressure existing within the regulated pressure steam header 28, the connection to this heater 28 being made by a pipe 68. The hydraulic regulating device, of course, is provided with the usual follow-up device whereby the pressure regulating valve 30 may be positioned in accordance with the pressure existing within the header 28 to maintain constant pressures therein. The hydraulically operated regulating device may be adjusted by means of a lever 69 which is connected by a chain or cable 70 to a crank 71 which is variably positioned by a proportioning motor 72. The lever 69 may adjust the hydraulically operated regulating device in any suitable manner and specifically it may adjust the tension of the spring of the pressure responsive device contained within the valve chest 67 which counteracts the pressures in the header 28 in a manner well known in the art.

This invention contemplates the use of a temperature responsive controller 74 of the variable resistance type which is connected by a capillary tube 75 to a bulb 76 located in the condensate 36 of the condenser 33. The controller 74, therefore, responds to changes in temperature of the condensate within the condenser 33, it being known that the condensate temperature increases as the condenser vacuum decreases. 50

It is also within the contemplation of this invention to utilize a temperature responsive controller 71 which is connected by a capillary tube 78 to a bulb 79 located within the main evaporator 10. Therefore, the controller 71 responds 73

to changes in temperature of the chilled cooling fluid in the evaporator 10.

Another temperature responsive controller is designated at 80 and is connected by a capillary tube 81 to a bulb 82 also located in the chilled cooling fluid in the evaporator 10. The controller 80, therefore, responds also to changes in temperature of the chilled cooling fluid in the main evaporator 10.

10 Located at some convenient point is a panel board designated at 83 and on this panel board 83 are mounted a program switch 84 operated by a motor 85, a proportioning relay 86, two off and on type relays 87 and 88, a variable resistance 15 range controller 89, a variable resistance differential controller 90 and a signal or alarm 91. The various motor switches, solenoids, relays, temperature responsive devices, variable resistances and alarms are all suitably connected together by conduits as shown in Figure 1. Electric power is supplied to the panel board 83 by means of a conduit 92 leading from some source of power (not shown).

15 The manner in which the various elements of 20 the control system are connected together and the construction of these control elements is shown diagrammatically in Figure 2. The temperature responsive controller 77 which responds to the temperature of the cooling fluid in the 25 main evaporator 10 may comprise a bellows 94 for operating a pivoted lever 95 which carries a double-ended mercury switch 96 having high temperature contacts at the left end thereof and low temperature contacts at the right end thereof. 30 The arrangement is such that when the temperature of the cooling fluid in the evaporator 10 is normal the switch 96 is in the position shown in Figure 2, but if the temperature in the evaporator 10 should increase as a result of an increased load being placed on the refrigerating mechanism the mercury switch 96 is tilted to a position opposite to that shown in Figure 2.

35 The temperature responsive device 74 which has the bulb 76 responding to the temperature of 40 the condensate within the condenser 33 may comprise a bellows 97 for operating a slider 98 with respect to a potentiometer coil 99. Upon an increase in temperature of the condensate the slider 98 is moved upwardly with respect to 45 the potentiometer coil 99 in the direction indicated by the character H, and upon a decrease in temperature the slider 98 is moved downwardly with respect to the potentiometer coil 99 in the direction indicated by the character C.

50 The temperature responsive device 80 which also responds to the temperature of the cooling fluid within the evaporator 10 may comprise a bellows 100 for operating a pivoted lever 101 which carries a mercury switch 102, the arrangement being such that when the temperature of the cooling fluid located within the evaporator 10 decreases to a predetermined low value the mercury switch is tilted to a circuit making position opposite to that shown in Figure 2.

55 The valve 56 which controls the supply of regulated steam to the secondary ejector 60 may be operated by a pitman 103 connected to a gear 104 mounted on a shaft 105 of the motor 57. The gear 104 may be driven through a reduction gear 60 train designated at 106 by a motor rotor 107 upon energization of a field winding 108. The shaft 105 carries a cam 109 for operating a switch arm 110 with respect to a contact 111. The shaft 105 also carries a cam 112 for operating a switch arm 113 with respect to spaced

60 contacts 114 and 115. When the valve 56 is in either its extreme open or extreme closed positions the switch arm 110 is maintained out of engagement with the contact 111, but when the valve 56 is in any position other than these extreme positions the switch arm 110 is held in engagement with the contact 111. The cam 109, the switch arm 110 and the contact 111 form a maintaining switch, the action of which will be pointed out more fully hereafter. The switch 10 arm 113 is maintained in engagement with the contact 114 when the valve 56 is in a closed position and with the contact 115 when the valve 56 is in an open position. The cam 112, the switch arm 113 and the contacts 114 and 115 form a 15 selecting switch the operation of which will also be pointed out more fully hereafter.

15 The valve 58 which controls the supply of high pressure steam to the secondary ejector 60 may be operated by a pitman 117 connected to 20 a gear 118 mounted on a shaft 119 of the motor 59. The gear 118 is driven through a reduction gear train generally designated at 120 by a motor rotor 121 upon the energization of the field winding 122. The motor 59 also includes a 25 maintaining switch mechanism which comprises a cam 123, a switch arm 124 and a contact 125 and a selecting switch mechanism which comprises a cam 126, a switch arm 127 and contacts 128 and 129.

30 The motor 20 which operates the four-way valve 19 which in turn controls the valve 16 associated with the main evaporator 10 may operate the valve 19 through a pitman 131 connected to a gear 132 mounted on a shaft 133. The gear 132 may be driven through a reduction gear train 134 by a motor rotor 135 upon the energization of a field winding 136. The motor 20 also includes a maintaining switch mechanism which comprises a cam 137, a switch arm 138 and a contact 139 and a selecting switch mechanism which comprises a cam 140, a switch arm 141 and contacts 142 and 143. At this point it will be noted that the valves 56 and 58 are in a closed position and the four-way valve 19 is in an open position.

35 The solenoid 52 for operating the four-way valve 51 which controls the operation of the valve 48 associated with the secondary evaporator 42 may comprise a coil 145 for controlling the operation of an armature 146. The valve 51 is in a closed position, being biased to this closed position by a compression spring 147. Upon energization of the coil 145 the compression spring 147 is compressed and the four-way valve 51 is moved to an open position.

40 The proportioning motor 72 which operates the crank 71 for adjusting the setting of the hydraulically operated pressure regulating valve may comprise a shaft 149 upon which the crank 71 is mounted. The shaft 149 carries a gear 150 which is driven through a reduction gear train 151 by motor rotors 152 and 153. The motor rotors 152 and 153 are placed in operation by energization of field windings 154 and 155, respectively, the arrangement being such that when the field winding 154 is energized the motor 72 is operated to move the crank 71 downwardly to raise the setting of the hydraulically operated pressure regulating device whereby the steam pressure within the regulated pressure header 28 is increased. When the field winding 155 is energized the crank 71 is moved upwardly to lower the setting of the pressure regulating device to decrease the steam pressure existing in the header 28. The shaft 149 also carries a bevelled gear 156 which meshes with 45

a bevelled gear 157 which in turn carries an abutment member 158. The abutment member 158 carries a slider 159 which cooperates with a balancing potentiometer coil 160. The abutment member 158 also carries spaced fingers 161 and 162 which are adapted to engage contacts 163 and 164 at either extreme position of the motor 12. The contacts 163 and 165 form a limit switch for preventing movement of the motor 12 beyond one extreme position upon energization of the field winding 154 and the contacts 164 and 166 form a limit switch for preventing movement of the motor 12 beyond the other extreme position upon the energization of the field winding 155.

This invention contemplates the use of a program switch designated at 84 for obtaining a predetermined sequence of operation. The program switch is shown to comprise an outer track 168 and an inner track 169, the outer track being made of insulating material and the inner track being made of conducting material. The outer track 168 has a series of spaced conducting portions 170, 171, 172, 173, 174 and 175, preferably located in the positions shown in Figure 2. The tracks 168 and 169 are bridged by a slider 176 which is carried by a bevelled gear 177 and the bevelled gear 177 meshes with another bevelled gear 178 mounted on a shaft 179. The shaft 179 also carries another bevelled gear 181 which engages with a second bevelled gear 182. Upon rotation of the bevelled gear 182 the slider 176 is rotated in a clockwise direction as indicated by the arrow to first cause contact between the conductor 170 and the track 169, then between the conductor 171 and the track 169 and so on until 180° of rotation is completed. When the slider 176 has been moved through 180° it comes to rest in a position bridging the conductor 174 and the track 169. Upon the next 180° of rotation the conductor 176 bridges the conductor 175 and the track 169 and comes to rest at the position shown in Figure 2.

The slider 176 is driven through these 180° cycles by the motor 85 which comprises a shaft 183 upon which is mounted the bevelled gear 182. The shaft 183 also carries a gear 184 which is driven through a reduction gear train 185 by a motor rotor 186 upon energization of a field winding 187. The shaft 183 also carries a cam 188 which operates a slider 189 with respect to a contact 190 forming a maintaining switching mechanism, the operation of which will be more clearly pointed out hereafter. The shaft 183 also carries a cam 191 which operates a switch arm 192 with respect to spaced contacts 193 and 194 which form a selecting switch, the operation of which will be more clearly pointed out hereafter. The reduction gear train 185 is so selected that the slider 176 will be rotated at a comparatively slow rate of speed through its 180° movements.

The proportioning relay 86 which is mounted on the panel board 83 is shown to comprise a step-down transformer 196 having a primary 197 and a secondary 198. One end of the secondary 198 is connected by wires 199, 200 and 201 to the left-hand ends of coils 202 and 203. Likewise the right-hand end of the secondary 198 is connected by wires 204, 205 and 206 to the right-hand ends of coils 207 and 208. The inner ends of the coils 202 and 207 are connected together and the inner ends of the coils 203 and 208 are also connected together. The coils 202 and 207 are adapted to operate a switch arm 209 with respect to spaced contacts 210 and 211, the

arrangement being such that when the coil 207 is energized more than the coil 202 the switch arm 209 is moved into engagement with the contact 211 and when the coil 202 is energized more than the coil 207 the switch arm 209 is moved into engagement with the contact 210. When the coils 202 and 207 are equally energized the switch arm 209 is maintained in a mid position as shown in the drawings. The contact 210 is connected by a wire 212 to a small number of turns of the coil 202 and the contact 211 is connected by a wire 213 to a small number of turns of the coil 207. The switch arm 209 is connected by a wire 214 to the junction of coils 203 and 208. The coils 203 and 208 operate a switch arm 215 with respect to contacts 215 and 217. When the coil 203 is energized more than the coil 208 the switch arm 215 is moved into engagement with the contact 216 and when the coil 208 is energized more than the coil 203 the switch arm 215 is moved into engagement with the contact 217. When the coils 203 and 208 are equally energized the switch arm 215 is maintained in the mid position as shown in the drawings.

The relay 87 mounted on the panel board 83 is shown to comprise a relay coil 219 for operating switch arms 220 and 221, the arrangement being such that when the relay coil 219 is energized the switch arms 220 and 221 are moved into engagement with contacts 222 and 223, respectively, and when the relay coil 219 is deenergized the switch arms 220 and 221 are moved into engagement with contacts 224 and 225 by means of springs, gravity or other means (not shown).

The relay 88 mounted on the panel board 83 is shown to comprise a relay coil 227 for operating a switch arm 228, the arrangement being such that when the relay coil 227 is deenergized the switch arm 228 is maintained in engagement with a contact 229 by means of springs, gravity or other means (not shown) and when the relay coil 227 is energized the switch arm 228 is moved out of engagement with the contact 229.

The range adjusting device 89 also mounted on the panel board 83 is shown to comprise resistances 230 and 231 which are engaged by sliders 232 and 233, respectively, the sliders 232 and 233 being moved simultaneously either to the right or to the left by manual manipulation thereof. The differential adjusting mechanism 90 also mounted on the panel board 83 is shown to comprise a resistance 234 engaged by a slider 235, the slider 235 being manually moved with respect to the resistance 234.

Line wires leading from some source of power (not shown) are designated at 237 and 238. The line wire 237 is connected by wires 239 and 240 to the left-hand end of the primary 197 of the relay 86 and the right-hand end thereof is connected by wires 241 and 242 to the other line wire 238.

The left-hand end of the coil 202 of the relay 86 is connected by wire 200, protective resistance 243, wires 244, 245 and 246, slider 232, resistance 230 and wire 247 to the upper end of the potentiometer coil 99 of the temperature responsive controller 74. The junction of wires 244 and 245 is connected by a wire 248 to the right-hand end of the balancing potentiometer 160, and the junction of wires 245 and 246 is connected by a wire 249 to the contact 223 of the relay 87. The right-hand end of the coil 207 is connected by a wire 205, a protective resistance 250 and wire 75

- 251 to the left-hand end of the balancing potentiometer coil 160 and by a wire 252, slider 233, resistance 231 and wire 253 to the lower end of the potentiometer coil 99 of the controller 74.
- 5 The junction of the coils 202 and 207 is connected by wires 254 and 257, resistance 234, slider 235 and wire 258 to the slider 159 associated with the balancing potentiometer coil 160. The junction of the coils 202 and 207 is also connected 10 by the wire 254 and a wire 255 to the switch arm 221 of the relay 87. The contact 225 is connected by a wire 256 to the slider 98 of the controller 74.
- From the above wiring connections of the relay 86 and the connections between the relay 86, the balancing potentiometer of the motor 72 and the potentiometer of the controller 74, it will be seen that the left-hand ends of the secondary and the coil 202 are connected to the 15 right-hand end of the balancing potentiometer 160 and the upper end of the potentiometer coil 99, and that the right-hand ends of the secondary 198 and the coil 207 are connected to the left-hand end of the balancing potentiometer 20 coil 160 and the lower end of the potentiometer coil 99. It is also seen that the junction of the coils 202 and 207 is connected to the slider 159 of the balancing potentiometer and the slider 98 of the controller 74. The secondary 198, the coils 30 202 and 207, the balancing potentiometer of the motor 72 and the potentiometer of the controller 74, therefore, are all connected in parallel.

The switch arm 215 controlled by the coils 203 and 208 is connected by wires 260 and 239 to the line wire 237. The contact 216 associated therewith is connected by a wire 261 to the limit switch contact 165 and the limit switch contact 163 is connected by a wire 262 to one end of the field winding 154. The contact 217 also associated 40 with the switch arm 215 is connected by a wire 263 to the limit switch contact 164 and the limit switch contact 166 is connected by a wire 264 to one end of the field winding 155. The other ends of the field windings 154 and 155 are connected together and are connected by wires 265 and 242 to the line wire 238.

The temperature responsive controller 74 and the proportioning motor 72 which adjusts the setting of the hydraulically operated pressure regulating valve 30 is utilized in this invention 50 to maintain a constant pressure drop across the orifice of the main steam jet ejector 32 at all times and the secondary steam jet ejector 60 when it is in operation. As the vacuum in the condenser 33 decreases the temperature of the condensate therein increases and this increase in temperature is utilized to increase the pressure setting of the pressure regulator whereby steam at a higher pressure is admitted to the 55 running nozzles 23 and 55 to increase the pressure thereat whereby the pressure drop across the orifices 32 and 60 is maintained constant.

The specific manner in which this mode of operation is brought about is clearly set forth in Figure 2. Upon an increase in temperature of the condensate in the evaporator 33 the bellows 97 expands to move the slider 98 upwardly with respect to the potentiometer coil 99. This upward movement causes partial short-circuiting 70 of the coil 202 through a circuit from the inner end of the coil 202 through wires 254, 255, switch arm 221, contact 225, wire 256, slider 98, the upper portion of the potentiometer coil 99, wire 247, resistance 230, slider 232, wires 246, 245 and 75 244, protective resistance 243 and wire 200 back

to the other end of the coil 202. Due to the parallel relationship pointed out above, this partial short circuiting of the coil 202 decreases the energization thereof and increases the energization of the coil 207. Due to this unbalanced relationship of the coils 202 and 207 the switch arm 209 is moved into engagement with the contact 211 which completes a short-circuit for the coil 208 from the inner end of the coil 208, through wire 214, switch arm 209, contact 211, 10 wire 213, a small number of turns of the coil 207 and wires 205 and 206 back to the other end of the coil 208. This short-circuiting of the coil 208 decreases the energization thereof and increases the energization of the coil 203. Due 15 to this unbalanced relationship of the coils 203 and 208 the switch arm 215 is moved into engagement with the contact 216 to complete a circuit from the line wire 237, through wires 239 and 260, switch arm 215, contact 216, wire 261, 20 limit switch contacts 165 and 163, wire 262, field winding 154 and wires 265 and 242 back to the other line wire 238. Completion of this circuit causes energization of the field winding 154 to move the crank 71 downwardly to raise the pressure setting of the hydraulically operated pressure regulating valve 30 whereby the pressure in the regulated pressure header 28 is increased to increase the steam pressure to the nozzles 23 and 55.

Movement of the crank 71 in such direction causes left-hand movement of the slider 159 with respect to the balancing potentiometer coil 160 and this left-hand movement causes a partial short-circuit through the coil 207, the circuit being completed from the inner end of the coil 207, through wire 254 and 257, resistance 234, slider 235, wire 258, slider 159, the left-hand portion of the balancing potentiometer coil 160, wire 251, protective resistance 250, and wire 205 back to the other end of the coil 207. This partial short-circuiting of the coil 207 decreases the energization thereof and increases the energization of the coil 202, it being remembered that the coil 207 was energized more than the coil 202 by the upward movement of the slider 98 with respect to the potentiometer coil 99. When the slider 159 has moved sufficiently far to the left with respect to the balancing potentiometer coil 160 so as to cause re-balancing of the coils 202 and 207, the switch arm 209 is moved out of engagement with the contact 211 to the mid-position shown in the drawing thus breaking the short-circuit through the coil 208. The coils 203 and 208 thereupon become equally energized and the switch arm 215 is moved out of engagement with the contact 216 to the mid-position shown in the drawings. This causes breaking of the circuit through the field winding 154 to prevent further downward movement of the crank 71 whereby the pressure regulator 30 is maintained in a position to deliver steam at the proper regulated pressure to the running nozzles 23 and 55 in accordance with the temperature of the condensate in the condenser 33.

Upon a drop in temperature of the condensate in the condenser 33 indicating directly that the condenser vacuum has increased and indirectly that the pressure drop across the orifices of the ejectors 32 and 60 is too large the slider 98 is moved downwardly with respect to the coil 99 to cause partial short-circuiting of the coil 207, this partial short circuit being completed from the inner end of the coil 207, through wires 254, 70 and 255, switch arm 221, contact 225, wire 256, 75

slider 98, the lower end of the potentiometer coil 99, wire 253, resistance 231, slider 233, wires 252 and 251, protective resistance 250 and wire 205 back to the outer end of the coil 207. This decreases the energization of the coil 207 and increases the energization of the coil 202 and due to this unbalanced relationship of the coils 202 and 207 the switch arm 209 is moved into engagement with the contact 210. This completes a short-circuit for the coil 203 from the inner end of the coil 203 through wire 214, switch arm 209, contact 210, wire 212, a small number of turns of the coil 202, and wires 200 and 201, back to the outer end of the coil 203. This short-circuiting of the coil 203 decreases the energization thereof and increases the energization of the coil 208, whereby the switch arm 215 is moved into engagement with the contact 217. Movement of the switch arm 215 into engagement with the contact 217 completes a circuit from the line wire 237, through wires 239 and 260, switch arm 215, contact 217, wire 263, limit switch contacts 164 and 166, wire 264, field winding 155 and wires 265 and 242 back to the other line wire 238. Completion of this circuit causes energization of the field winding 155 to move the crank 71 upwardly to lower the setting of the hydraulically operated pressure regulating valve 30 whereby the steam pressure within the header 28 is decreased to supply steam at a less pressure to the running nozzles 23 and 55 whereby the pressure drop across the ejectors 32 and 60 is decreased. Movement of the crank 71 upwardly in this manner causes right-hand movement of the slider 159 with respect to the balancing potentiometer coil 160, this right-hand movement causing a partial short-circuit for the coil 202 which partial short-circuit is completed from the inner end of the coil 202 through wires 254 and 257, resistance 234, slider 235, wire 258, slider 159, the right-hand end of the balancing potentiometer coil 160, wires 248 and 244, protective resistance 243 and wire 200 back to the outer end of the coil 202. Completion of this partial short-circuit decreases the energization of the coil 202 and increases the energization of the coil 207, it being remembered that the coil 202 was energized more than the coil 207 by the downward movement of the slider 87 with respect to the potentiometer coil 99. When the slider 159 has moved sufficiently far to the right with respect to the balancing potentiometer coil 160 so as to re-balance the energization of the coils 202 and 207 the switch arm 209 is moved out of engagement with the contact 210 to the midposition shown in the drawings. This breaks the short-circuit through the coil 203 causing equal energization of the coils 203 and 208, which in turn causes movement of the switch arm 215 out of engagement with the contact 217 whereby the circuit through the field winding 155 is broken. This prevents further upward movement of the crank 71 and the hydraulically operated pressure regulating valve 30 is maintained at a setting in accordance with the temperature decrease in the condenser 33.

In this manner, the pressure drop across the orifices of the ejectors 32 and 60 are maintained constant regardless of the value of the vacuum existing within the condenser 33, since steam at a higher pressure is supplied to the running nozzles 23 and 55 when the condenser vacuum decreases. This constant pressure drop across the orifices entrains a constant amount of vapor 75 from the evaporators whereby the evaporator

vacuum is maintained constant under all conditions.

It will be noted that the circuits through the coils 203 and 208 of the relay 86 are completed through a small number of turns of the coils 5 202 and 207, whereby the switch arm 209 is held forcibly in engagement with the contacts 210 or 211 to prevent the occurrence of relay chatter. The protective resistances 243 and 250 are provided to prevent complete short-circuiting of the 10 coils 202 and 207 whereby burning out of the same is prevented.

The range adjusting rheostat 89 is provided in the circuits of the potentiometer coil 99 for raising or lowering the control point of controller 15 74. Movement of the sliders 232 and 233 simultaneously towards the right as viewed in Figure 2 decreases the resistance in series with the lower portion of the potentiometer coil 99 and increases the resistance in series with the upper portion 20 of the potentiometer coil 99. This has the same effect as moving the slider 98 downwardly with respect to the coil 99. The motor 72 is operated to move the crank arm 71 upwardly to lower the pressure setting of the hydraulically operated 25 pressure regulating valve 30 with respect to the temperature of the condensate within the condenser 33. Therefore, this right-hand movement of the sliders 232 and 233 lowers the pressure of the steam admitted to the running nozzles 55 whereby the drop in pressure across the orifices of the ejectors 32 and 60 is decreased. Movement of the sliders 232 and 233 simultaneously to the left decreases the resistance in series with the upper portion of the potentiometer coil 99 and increases the resistance in series with the lower portion of the potentiometer coil 99. This has the same effect as moving the slider 98 upwardly with respect to the coil 99 whereby the crank arm 71 is moved downwardly to raise the setting of the hydraulically operated pressure regulating valve 30 whereby steam at a higher pressure is admitted to the running nozzles 55. This increases the drop pressures across the orifices of the ejectors 32 and 60. Therefore, it is seen that by manually manipulating the range adjusting rheostat 89 the pressure drop across the orifices of the ejectors 32 and 60 may be adjusted at will to maintain desired values of vacuum in the evaporators 10 and 42.

The differential adjusting rheostat 90 is utilized for adjusting the differential of operation of the controller 74. For a given movement of the slider 98 of the controller 74, a given movement of the slider 159 with respect to the balancing potentiometer coil 160 is required to re-balance the coils 202 and 207. By moving the slider 235 upwardly with respect to the resistance 234 the resistance in series with the balancing potentiometer is decreased and, therefore the 50 slider 159 will not have to move as far with respect to the balancing potentiometer coil 160 to re-balance the coils 202 and 207. It follows then that upward movement of the slider 235 with respect to the resistance 234 requires a greater 55 movement of the control slider 98 with respect to the potentiometer 99 to operate the motor 72 through a given distance. Downward movement of the slider 235 with respect to the resistance 234 increases the resistance in series with the 60 balancing potentiometer whereby greater movement of the slider 159 with respect to the balancing potentiometer coil 160 is required to re-balance the coils 202 and 207. It, therefore, follows that downward movement of the slider 235 65

with respect to the resistance 234 requires lesser movement of the control slider 98 with respect to its potentiometer coil 99 to move the motor 72 through a given distance. In this manner, the differential of the control system may be adjusted whereby the sensitivity of the control system may be selected to suit the operating characteristics of the refrigerating mechanism.

With the parts in the position shown in Figure 1, the main ejector mechanism is in operation and the valve 16 is in an open position whereby steam is being supplied to the running nozzles 23 to chill the cooling fluid in the main evaporator 10. The secondary refrigerating mechanism is not in operation and the evaporator 42 is disconnected from the condenser 33 by the valve 48 and the starting nozzles 54 and the running nozzles 55 are inoperative by reason of the valves 58 and 56 being closed. The main refrigerating mechanism is, therefore, providing all of the cooling. If the load on the main refrigerating mechanism should increase the temperature of the chilled cooling fluid within the evaporator 10 would likewise increase. This increase in temperature of the evaporating fluid operates on the bulb 79 to move the mercury switch 96 to the position opposite to that shown in Figure 2. This movement of the mercury switch 96 by the increased demand on the refrigerating mechanism completes a circuit from the line wire 237, through wires 267 and 268, the high temperature contacts of the mercury switch 96, wire 269, contact 194, switch arm 192, wire 270, field winding 187 and wire 271 back to the other line wire 238. Completion of this circuit causes energization of the field winding 187 to start rotation of the slider 176 of the program switch 84 in a clockwise direction. Energization of the field winding causes rotation of the cam 188 to move the switch arm 189 into engagement with the contact 190 to complete a maintaining circuit from the line wire 237, through wires 267 and 272, contact 190, switch arm 189, wire 273, field winding 187 and wire 271 back to the other line wire 238. This circuit maintains the field winding 187 energized until such time as the slider 176 of the program switch 84 is moved through 180° at which time the cam 191 moves the switch arm 192 out of engagement with the contact 194 and into engagement with the contact 193 to break the starting circuit through the high temperature contacts of the mercury switch 96 and the switch arm 189 is moved out of engagement with the contact 190 to break the maintaining circuit through the field winding 187, whereby the slider 176 of the program switch 84 is maintained in a position removed from the position shown in the drawing by 180°.

As pointed out above, the clockwise rotation of the slider 176 of the program switch 84 is relatively slow and when the slider 176 moves into engagement with the conductor 170 a circuit is completed from the line wire 237, through wire 276, inside track 169, slider 176, conductor 170, wire 277, contact 143 of motor 20, switch arm 141, wire 278 and field winding 136 back to the other line wire 238. Completion of this circuit causes energization of the field winding 136 to start movement of the valve 19 towards a closed position. When the valve 19 has been so started in its closing movement the cam 137 moves the switch arm 138 into engagement with the contact 139 to complete a maintaining circuit from the line wire 237 through wire 277, contact 139, switch arm 138, wire 280 and field

winding 136 back to the other line wire 238. This insures complete closing movement of the valve 19 and when the valve has been closed the switch arm 138 is moved out of engagement with the contact 139 to break the circuit to the field winding 136 and the switch arm 141 is moved into engagement with the contact 142 to place the motor in condition for opening movement. Closing of the four-way valve 19 in this manner causes operation of the hydraulic motor 18 to move the gate 17 to close the valve 16, whereby communication between the main evaporator 10 and the condenser 33 is broken.

Further clockwise movement of the slider 176 into engagement with the conductor 171 completes a circuit from the line wire 237, through wire 276, inside track 169, slider 176, conductor 171, wires 282 and 283, contact 128 of the motor 59, switch arm 127, wire 284 and field winding 122 back to the other line wire 238. Completion of this circuit causes energization of the field winding 122 to start movement of the valve 58 towards an open position. Complete opening movement of the valve 58 is insured by a circuit from the line wire 237, through wire 285, contact 125, switch arm 124, wire 286 and field winding 122 back to the other line wire 238. This circuit through the field winding 122 is maintained until the valve 58 is moved to a complete open position at which time the switch arm 124 is moved out of engagement with the contact 125 and the switch arm 127 is moved into engagement with the contact 129. It is, therefore, seen that after the valve 16 associated with the main evaporator 10 has been closed the valve 58 is opened, to supply steam to the starting nozzles 54 of the secondary ejector to produce a vacuum in the nozzle box 53.

Movement of the slider 176 into engagement with the conductor 171 also completes a starting circuit from the conductor 171, through wires 282 and 288, contact 224 of the relay 87, switch arm 220, wire 289, relay coil 219 and wire 290 back to the line wire 238. Completion of this circuit causes energization of the relay coil 219 to move the switch arms 220 and 221 into engagement with the contacts 222 and 223. Movement of the switch arm 220 into engagement with the contact 222 completes a maintaining circuit from the line wire 237, through wire 291, contact 229 of the relay 88, switch arm 228, wire 292, contact 222, switch arm 220, wire 289, relay coil 219 and wire 290 back to the other line wire 238. Completion of this circuit maintains the relay coil 219 energized and maintains the switch arm 220 and 221 in engagement with the contacts 222 and 223, respectively.

Movement of the switch arm 221 out of engagement with the contact 225 breaks the circuit between the slider 98 of the controller 74 and the junction of the coils 202 and 207 whereby the controller 74 is rendered inoperative to control the proportioning motor 72 and consequently the hydraulically operated pressure regulating valve. Movement of the slider 221 into engagement with the contact 223 completes a short-circuit for the coil 202 of the relay 86 which circuit may be traced from the inner end of the coil 202, through wires 254 and 255, switch arm 221, contact 223, wires 249, 245 and 244, protective resistance 243 and wire 200 back to the outer end of the coil 202. This decreases the energization of the coil 202 and increases the energization of the coil 207 to cause downward movement of the crank 71 of the motor 72 to increase the pressure setting 75

of the hydraulically operated pressure regulating valve. Since the short-circuit of the coil 202 is substantially complete, complete downward movement of the crank 71 is brought about and, 5 therefore, the pressure regulating valve is adjusted to its highest pressure setting whereby relatively high pressure steam is admitted in the steam header 28.

Further clockwise movement of the slider 176 10 into engagement with the conductor 172 completes a circuit from the line wire 237, through wire 276, inside track 169, a slider 176, conductor 172, wire 294, contact 114 of the motor 57, switch arm 113, wire 295 and field winding 108 back 15 to the other line wire 238. This causes energization of the field winding 108 to move the valve 56 to its open position. Opening movement of the valve 56 is assured by a maintaining circuit completed from the line wire 237, through 20 wire 296, contact 111, switch arm 110, wire 297 and field winding 108 back to the other line wire 238. When the valve 56 is moved to its 25 completely open position the switch arm 110 is moved out of engagement with the contact 111 to break the circuit through the field winding 108 and the switch arm 113 is moved into engagement with the contact 115. In this manner, the valve 56 is moved to an open position 30 whereby relatively high pressure steam from the regulated pressure header 28 is admitted to the running nozzles 55 to maintain the vacuum within in the nozzle box 53.

Further clockwise movement of the slider 176 35 into engagement with the conductor 173 completes a circuit from the line wire 237 through wire 276, inside track 169, slider 176, conductor 173, wire 299, contact 129 of the motor 59, switch arm 127, wire 284 and field winding 122 back to the other line wire 238. This causes closing movement of the valve 58 and closing movement 40 of this valve is assured by means of the maintaining circuit outlined above. Closing of the valve 58 prevents the further supply of high pressure steam to the starting nozzles 54 of the secondary ejector.

Further rotation of the slider 176 causes engagement thereof with the conductor 174 and, as pointed out above, the slider 176 is maintained in this position in contact with the conductor 174. A circuit is completed from the line wire 50 237 through wire 276, inside track 169, slider 176, conductor 174, wires 301, 302 and 303 to the contact 142 of the motor 20, switch arm 141, wire 278 and field winding 136, back to the other line wire 238. This causes energization of field 55 winding 136 to move the valve 19 to an open position and the opening movement of this valve is assured by the maintaining circuit outlined above. Opening movement of the four-way valve 19 causes operation of the hydraulic motor 18 to move the valve 16 to open position whereby communication between the primary evaporator 10 and the condenser 33 is again established and the primary ejector mechanism is again placed in operation.

A circuit is also completed from the conductor 174 through wires 301, 302 and 304, coil 145 of the solenoid 52 and wire 305 back to the other line wire 238. Completion of this circuit causes energization of the coil 145 to compress the spring 70 147 and to move the four-way valve 51 to an open position. Movement of the four-way valve 51 to the open position causes operation of the hydraulic motor 50 to move the valve 48 to open position to establish communication between the secondary evaporator and the condenser 33

whereby the secondary ejector mechanism is placed in operation.

A circuit is also completed from the conductor 174 through wires 301 and 306, relay coil 227 of the relay 88 and wire 307 back to the line wire 238. Completion of this circuit causes energization 5 of the relay coil 227 to move the switch arm 228 out of engagement with the contact 229 whereby the maintaining circuit for the relay coil 219 is broken and the switch arms 220 and 221 are 10 moved out of engagement with the contacts 221 and 222, respectively, and into engagement with the contacts 224 and 225, respectively. Movement of the switch arm 221 out of engagement with the contact 223 breaks the short circuit 15 through the coil 202 of the relay 86 to lower the setting of the hydraulically operated pressure regulating valve 30 and movement of the switch arm 221 into engagement with the contact 225 again places the relay 86 and, consequently, the 20 motor 12 under the control of the temperature responsive controller 74 whereby the pressure of the steam within the header 28 is regulated in accordance with the temperature of the condensate within the condenser to maintain a 25 constant pressure drop across the orifice of the ejectors 32 and 60 in the manner pointed out above.

Therefore, it is seen that normally the main refrigerating apparatus is in operation and that when the load on that refrigerating apparatus increases to such a value as to cause an increase in the chilled cooling water in the evaporator 10, the program switch 84 is placed in operation to perform a predetermined sequence of operation. First, the valve 16 associated with the main evaporator 10 is moved to a closed position whereby the backing up of steam in the evaporator 10 is prevented. Secondly, the valve 58 is opened to supply steam to the starting nozzles of the secondary ejector and the hydraulically operated pressure regulating valve 30 is adjusted to its highest pressure setting whereby steam at relatively high pressure is admitted to the steam header 28. Thirdly, the valve 56 is moved to an open position whereby this high pressure steam in the regulated pressure steam header 28 is admitted to the running nozzles 55 of the secondary ejector. Fourthly, the valve 58 is moved to a closed position shutting off the supply of steam to the starting nozzles 54 of the secondary ejector. Fifthly, the valve 16 is opened and communication between the main evaporator 10 and the condenser 33 is re-established, the valve 48 is opened and communication between the secondary evaporator 42 and the condenser 33 is 50 established, and the control of the hydraulically operated pressure regulating valve is returned to the temperature responsive controller 74 whereby the pressure in the regulated steam header 28 is decreased and the pressures therein are regulated in accordance with the temperature of the condensate within the condenser 33. In this manner, both the main ejector and the secondary ejector are placed in operation to supply sufficient cooling to make up for the increased 55 load on the refrigerating mechanism.

When the load on the refrigerating mechanism decreases the temperature of the chilled water within the main evaporator 10 will also decrease and when the temperature of this chilled water has decreased to a given value the mercury switch 96 of the temperature responsive controller 77 is tilted to the position shown in the drawings whereby contact between the low temperature contacts is established. This causes com- 70 75

pletion of a circuit from the line wire 237, through wires 267 and 268, the low temperature contacts of the mercury switch 96, wire 274, contact 93, switch arm 192, wire 270, field winding 5 187 and wire 271 back to the other line wire 238. Completion of this circuit causes another 180° rotation of the slider 176 of the program switch 84. Complete movement of the slider 176 through 10 180° to the position shown in Figure 2 is assured by the maintaining circuit outlined above.

Movement of the slider 176 out of engagement with the contact 174 breaks the circuit through the relay coil 277 of the relay 88, whereby the switch arm 228 is moved into engagement with 15 the contact 229 but since the maintaining circuit through the relay coil 219 of the relay 87 was previously broken the relay coil 219 may not again be energized until such time as the slider 176 moves into engagement with the conductor 20 171 upon a demand for more cooling. Movement of the slider 176 out of engagement with the conductor 174 also breaks the circuit through the coil 145 of the solenoid 52, whereby the compression spring 141 causes the valve 51 to be 25 moved to a closed position. This closing movement of the valve 51 causes operation of the hydraulic motor 50 to move the valve 48 to a closed position breaking communication between the secondary evaporator 42 and the condenser 33. 30 Movement of the slider 176 into engagement with the conductor 175 completes a circuit from the line wire 237, through wire 276, inside track 169, slider 176, conductor 175, wire 309, contact 115, switch arm 113, wire 295 and field winding 35 108 back to the other line wire 238. Completion of this circuit causes energization of the field winding 108 to move the valve 56 to a closed position, closing movement of the valve being assured by the maintaining circuit outlined above. 40 Movement of the valve 56 to a closed position prevents the further supply of steam to the running nozzles 55 of the secondary ejector. The slider 176 continues to move in a clockwise direction until it has completed 180° of rotation at 45 which time it comes to rest in the position shown in Figure 2.

From the above, it is seen that when the load on the refrigerating mechanism as a whole decreases so as to not require the operation of the secondary refrigerating mechanism, this secondary refrigerating mechanism is placed out of operation in the following steps: First, the valve 48 is moved to a closed position breaking communication between the secondary evaporator 42 and the condenser 33 and, secondly, the supply of steam to the running nozzles 55 of the secondary evaporator is shut off. The main refrigerating mechanism remains in operation to supply the necessary cooling at this particular load requirement. Upon an increase in load the sequence of operation outlined above will again be followed and the secondary refrigerating mechanism will again be placed in operation.

A primary 312 of a step-down transformer 311 having a secondary 313 is connected across the line wires 237 and 238. If the load on the refrigerating mechanism should decrease so that no cooling by the refrigerating mechanism is required the temperature of the chilled water within 50 the main evaporator 10 will decrease to a predetermined low value and the bulb 82 located within the evaporator 10 causes contraction of the bellows 100 of the controller 80 in response to this predetermined low temperature. Contraction of the bellows 100 causes tilting of the

switch 102 to a circuit making position to complete a circuit from one end of the secondary 5 313, through wire 314, mercury switch 102, wire 315, signal or alarm 91 and wire 316 back to the other end of the secondary 313. Completion of this circuit causes operation of the alarm 91 to indicate to the engineer in charge of the refrigerating mechanism that no more cooling is required and that the main ejector mechanism should be closed down. In order to close down 10 the main refrigerating mechanism all that is required is closure of the manually operated valve 29 whereby the supply of steam to the running nozzles 23 is shut off.

Although I have shown the temperature responsive controller 74 to be responsive to the temperature of the condensate of the condenser 33 for the purpose of maintaining a constant pressure drop across the ejectors regardless of the vacuum existing within the condensers, other 20 means for accomplishing this result may be utilized. For instance, the controller 74 could respond directly to the vacuum existing within the condenser to adjust the setting of the pressure regulating valves to maintain the pressure drop 25 across the ejectors constant. Also, the temperature responsive controller 74 could respond to the temperature of the discharge condensing fluid, or in case a cooling tower is used the controller 74 could respond to the temperature of the condensing fluid flowing from the cooling tower to 30 the condenser.

Although I have shown one form of my invention for purposes of illustration, other forms thereof may become apparent to those skilled in 35 the art and, consequently, this invention is to be limited only by the scope of the appended claims and the prior art.

I claim as my invention:

1. In a refrigerating system having a source of 40 steam, an evaporator, an ejector and a condenser, the combination of means responsive to a call for cooling for supplying steam at a high pressure to the ejector for a period of time for placing the refrigerating system in operation and then supplying steam at a reduced pressure to the ejector 45 for maintaining the refrigerating system in operation, and means for regulating the supply of steam at the reduced pressure to maintain the pressure drop across the ejector constant. 50

2. In a refrigerating system having a source of steam, an evaporator, a condenser and an ejector, the combination of means responsive to the temperature of the chilled cooling fluid in the evaporator, a program switch controlled by said 55 temperature responsive means, means for supplying steam at high pressures and at reduced pressures to the ejector, said means being controlled by said program switch, the arrangement being such that upon an increase in chilled cooling fluid 60 temperature steam is supplied to the ejector at high pressure for an interval of time to place the refrigerating system in operation and then at a reduced pressure to maintain the refrigerating system in operation. 65

3. In a refrigerating system having a source of steam, an evaporator, a condenser and an ejector, the combination of means responsive to the temperature of chilled cooling fluid in the evaporator, a program switch controlled by said temperature 70 responsive means, means for supplying steam at high pressures and at reduced pressures to the ejector, said means being controlled by said program switch, the arrangement being such that upon an increase in chilled cooling fluid tempera- 75

ture steam is supplied to the ejector at high pressure for an interval of time to place the refrigerating system in operation and then at a reduced pressure to maintain the refrigerating system in operation, pressure regulating means for maintaining the supply of steam at a constant reduced pressure, and means responsive to a condition in the condenser for adjusting said pressure regulating means to maintain the pressure drop across the ejector constant regardless of fluctuations in condenser vacuum.

4. In a refrigerating system having an evaporator, an ejector, a steam supply and a condenser, the combination of a first valve means between the evaporator and the ejector, a second valve means for controlling the supply of steam to the ejector, a pressure regulating valve means for maintaining the steam pressure constant, adjusting means for the pressure regulating valve, and means responsive to a call for cooling, first, for operating the adjusting means to adjust the pressure regulating valve means to supply high pressure steam, second, for opening the second valve means to supply steam at high pressure to the ejector, and third, for operating the adjusting means to allow normal pressure regulation of the steam supply at a reduced pressure and for opening the first valve means.

5. In a refrigerating system having an evaporator, an ejector, a steam supply and a condenser, the combination of a first valve means between the evaporator and the ejector, a second valve means for controlling the supply of steam to the ejector, a pressure regulating valve means for maintaining the steam pressure constant, adjusting means for the pressure regulating valve, means responsive to a call for cooling, first, for operating the adjusting means to adjust the pressure regulating valve means to supply high pressure steam, second, for opening the second valve means to supply steam at high pressure to the ejector and, third, for operating the adjusting means to allow normal pressure regulation of the steam supply at a reduced pressure and for opening the first valve means, and means for adjusting the pressure regulating valve means in accordance with a condition in the condenser to maintain the pressure drop across the ejector constant.

6. In a refrigerating system having an evaporator, an ejector, a steam supply and a condenser, the combination of starting and running nozzles for the ejector, first valve means controlling communication between the evaporator and the ejector, second valve means for controlling the supply of high pressure steam to the starting nozzles, third valve means for controlling the supply of steam to the running nozzles, pressure regulating means controlling the pressure of the steam controlled by the third valve means, adjusting means for the pressure regulating means, and means responsive to a demand for cooling, first for opening the second valve means to admit high pressure steam to the starting nozzles and for operating the adjusting means to admit high pressure steam to the third valve means, second, for opening the third valve means to admit high pressure steam to the running nozzles, third, for closing the second valve means, and fourth, for opening the first valve to communicate the evaporator with the ejector and for operating the adjusting means to admit steam to the running nozzles at a reduced constant pressure.

7. In a refrigerating system having an evaporator, an ejector, a steam supply and a con-

denser, the combination of starting and running nozzles for the ejector, first valve means controlling communication between the evaporator and the ejector, second valve means for controlling the supply of high pressure steam to the starting nozzles, third valve means for controlling the supply of steam to the running nozzles, pressure regulating means controlling the pressure of the steam controlled by the third valve means, adjusting means for the pressure regulating means, means responsive to a demand for cooling, first, for opening the second valve means to admit high pressure steam to the starting nozzles and for operating the adjusting means to admit high pressure steam to the third valve means, second, for opening the third valve means to admit high pressure steam to the running nozzles, third, for closing the second valve means, and fourth, for opening the first valve to communicate the evaporator with the ejector and for operating the adjusting means to admit steam to the running nozzles at a reduced constant pressure, and means responsive to a condition in the condenser for controlling the adjusting means to regulate the steam supplied to the running nozzles in accordance with condenser vacuum.

8. In a refrigerating system having a steam supply, a condenser, primary and secondary ejectors and primary and secondary evaporators, first valve means controlling communication between the primary ejector and the primary evaporator, second valve means controlling communication between the secondary ejector and the secondary evaporator, pressure regulating means for controlling the supply of steam to the primary and secondary ejectors, adjusting means for the pressure regulating means, third valve means for additionally controlling the supply of steam to the secondary ejector, and means responsive to an increase in temperature of the chilled cooling fluid in the primary evaporator for, first, closing the first valve means, second, for operating the adjusting means to raise the setting of the pressure regulating means, third, for opening the third valve means to admit high pressure steam to the secondary ejector, and fourth, for opening the first and second valve means and for operating the adjusting means to lower the setting of the pressure regulating means.

9. In a refrigerating system having a steam supply, a condenser, primary and secondary ejectors and primary and secondary evaporators, first valve means controlling communication between the primary ejector and the primary evaporator, second valve means controlling communication between the secondary ejector and the secondary evaporator, pressure regulating means for controlling the supply of steam to the primary and secondary ejectors, adjusting means for the pressure regulating means, third valve means for additionally controlling the supply of steam to the secondary ejector, means responsive to an increase in temperature of the chilled cooling fluid in the primary evaporator for, first, closing the first valve means, second, for operating the adjusting means to raise the setting of the pressure regulating means, third, for opening the third valve means to admit high pressure steam to the secondary ejector, and fourth, for opening the first and second valve means and for operating the adjusting means to lower the setting of the pressure regulating means, and means responsive to a condition in the condenser for controlling the adjusting means to regulate

the steam supplied to the primary and secondary ejectors in accordance with condenser vacuum.

10. In a refrigerating system having a source of steam, an evaporator, an ejector and a condenser, the combination of a valve for controlling the supply of steam to the ejector, means responsive to steam pressure down stream of the valve, means responsive to the vacuum in the condenser, means responsive to a demand for cooling, and 10 means controlled by said steam pressure responsive means, said vacuum responsive means and said cooling demand responsive means for operating said valve for a period of time to deliver steam at a relatively high pressure to the ejector 15 and for subsequently operating said valve to deliver steam at a reduced constant pressure which is adjusted in accordance with condenser vacuum.

11. In a refrigerating system having a source 20 of steam, an evaporator, an ejector and a condenser, the combination of valve means for controlling the supply of steam to the ejector, a pressure regulating valve means for maintaining the steam pressure constant, adjusting means for 25 the pressure regulating valve, and means responsive to a call for cooling, first, for operating the adjusting means to adjust the pressure regulating valve means to supply high pressure steam, second, for opening the valve means to supply 30 steam at high pressure to the ejector and, third, for operating the adjusting means to allow normal pressure regulation of the steam supply at a reduced pressure.

12. In a refrigerating system having a source 35 of steam, an evaporator, an ejector and a condenser, the combination of valve means for controlling the supply of steam to the ejector, a pressure regulating valve means for maintaining the steam pressure constant, adjusting means for 40 the pressure regulating valve, and means responsive to a call for cooling, first, for operating the adjusting means to adjust the pressure regulating valve means to supply high pressure steam, second, for opening the valve means to supply 45 steam at high pressure to the ejector and, third, for operating the adjusting means to allow normal pressure regulation of the steam supply at a reduced pressure, and means for adjusting the pressure regulating valve means in accordance 50 with a condition in the condenser to maintain the pressure drop across the ejector constant.

13. In a refrigerating system having a source 55 of steam, an evaporator, an ejector and a condenser, the combination of starting and running nozzles for the ejector, first valve means for controlling the supply of high pressure steam to the starting nozzles, second valve means for controlling the supply of steam to the running nozzles, pressure regulating valve means controlling the 60 pressure of the steam controlled by the second valve means, adjusting means for the pressure regulating means, and means responsive to a demand for cooling, first, for opening the first valve means to admit high pressure steam to the starting nozzles and for operating the adjusting means to admit high pressure steam to the second valve means, second, for opening the second valve means to admit high pressure steam to the running nozzles, third, for closing the first valve means, and fourth, for operating the adjusting means to admit steam to the running nozzles at a reduced constant pressure.

14. In a refrigerating system having a source 75 of steam, an evaporator, an ejector and a condenser, the combination of starting and running

nozzles for the ejector, first valve means for controlling the supply of high pressure steam to the starting nozzles, second valve means for controlling the supply of steam to the running nozzles, pressure regulating valve means controlling the pressure of the steam controlled by the second valve means, adjusting means for the pressure regulating means, means responsive to a demand for cooling, first, for opening the first valve means to admit high pressure steam to the starting 10 nozzles and for operating the adjusting means to admit high pressure steam to the second valve means, second, for opening the second valve means to admit high pressure steam to the running nozzles, third, for closing the first valve means, and fourth, for operating the adjusting means to admit steam to the running nozzles at a reduced constant pressure, and means responsive to a condition in the condenser for controlling the adjusting means to regulate the steam supplied to the running nozzles in accordance with condenser vacuum.

15. In a refrigerating system having a source of steam, an evaporator, an ejector and a condenser, the combination of means for supplying steam to the ejector at a high pressure for a predetermined period of time in response to a call for cooling for placing the refrigerating system in operation, and means for subsequently supplying steam to the ejector at a reduced pressure for maintaining the refrigerating system in operation.

16. In a refrigerating system having a source of steam, an evaporator, a condenser and an ejector, said ejector including a plurality of nozzles, a starting valve means in control of the supply of steam to said nozzles, a running valve means in control of the supply of steam to said nozzles, a third valve means controlling communication between the evaporator and the ejector, a program switch means, an electric motor controlling the operation of said switch means, means responsive to a rise in temperature of the chilled cooling fluid in the evaporator to a predetermined value to energize said motor to cause operation of said program switch means, circuit connections controlled by said program switch means to cause the opening of the starting valve means, followed by the opening of the running valve means, and to subsequently cause opening of the third valve means and closure of the starting valve means, said motor again causing operation of said program switch means in response to a drop in temperature of the chilled cooling fluid in the evaporator to a predetermined value, and circuit connections operated by this last operation of the program switch means to cause the closure of said running valve means and the third valve means.

17. In a refrigerating system having a source of steam, an evaporator, a condenser and an ejector, said ejector including a plurality of nozzles, a starting valve means in control of the supply of steam to said nozzles, a running valve means in control of the supply of steam to said nozzles, a third valve means controlling communication between the evaporator and the ejector, hydraulic motor means controlling said third valve means, a program switch means, an electric motor controlling the operation of said switch means, means responsive to a rise in temperature in the chilled cooling fluid to a predetermined value in the evaporator to energize said motor to cause operation of said program switch means, circuit connections controlled by said

program switch means to first cause the opening of the starting valve means, to then cause the opening of the running valve means, to subsequently cause opening of the third valve means by means of the hydraulic motor means and closure of the starting valve means, said motor again causing operation of the program switch means in response to a drop in temperature of

the chilled cooling fluid in the evaporator to a predetermined value, and circuit connections operated by this last operation of the program switch means to cause the hydraulic motor means to move the third valve means to closed position and to cause closure of the running valve means. 5
